UNITED STATES PATENT OFFICE.

HERMAN L. GREVE, OF NEW YORK, N. Y., ASSIGNOR TO INTERNATIONAL MAILING TUBE AND WRAPPER COMPANY, A CORPORATION OF NEW YORK.

MAILING-WRAPPER.

1,376,871.

Specification of Letters Patent.

Patented May 3, 1921.

Application filed July 9, 1919. Serial No. 309,743.

To all whom it may concern:

Be it known that I, HERMAN L. GREVE, citizen of the United States, and resident of the city of New York, in the county of Kings and State of New York, have invented certain new and useful Improvements in Mailing-Wrappers, of which the following is a specification.

My invention relates to mailing wrappers and the object of my invention is to provide an adjustable wrapper of this character for mailing books and small boxes, etc., that may be easily opened for inspection and the outward character of the article mailed may be inspected without unwrapping the wrapper.

A further object is to provide a wrapper that may be re-used several times, depending on its condition after use.

Referring to the drawings which form a part of this application,

Figure 1 is a view of the inner side of the body portion of a wrapper embodying my invention.

Fig. 2 is a view of the inner side of the body portion which with that shown in Fig. 1 forms the complete body portion of the wrapper.

Fig. 3 is a view of the inner side of the wrapper after the two portions have been joined together.

Fig. 4 is an enlarged view of the wrapper shown in cross section on line X—X of Fig. 3.

Fig. 5 is a perspective view of the wrapper illustrating the overlying inner flaps or extensions D which extend over the ends of the book inclosed.

Fig. 6 is a perspective view of the opposite side of the wrapper with the book inclosed and the fastening means in place.

A and B respectively indicate the two body portions of the wrapper, each formed of strong flexible paper or other suitable material, and each having its outer edge reinforced by a thin sheet of relatively stiff material such as lead, zinc or soft iron indicated by C, which is folded over the edge of the body portion as shown at E and serves also to hold one side of the flap portion D as clearly shown in Fig. 4. This metal portion C is scored at the places where the metal must be bent considerably as illus-

trated at F to permit it to give easily at these points. The portions A and B are made so as to be adjustable laterally relative to each other, the portion A having an extension illustrated in dotted lines, formed in the blank and indicated by G, the ends G—G' respectively of which are bent and passed through slots H—H respectively and cemented together as illustrated in dotted lines at I in Fig. 3. This construction forms a band and guide combination which holds the parts together in adjustable relation so that it can be made of a width to correspond to the length of the book to be wrapped. The book is inclosed in the wrapper as illustrated in Figs. 5 and 6, the flap portions D extending from the edge portions C over the respective ends of the book J and held by the body portions, the whole being held together by the button and string combination K and K' as illustrated. By this construction the book is well protected and yet the wrapper does not enfold so completely as to prevent ready inspection by the Post Office authorities. The simplicity of the construction is such that further description is deemed unnecessary.

Having thus described my invention I claim as new and desire to secure by Letters Patent:—

1. A wrapper made of thin flexible material consisting of two longitudinally extending portions held together and relatively adjustable laterally and having a side flap connected to one of said portions and adapted to extend therefrom over the end of the article inclosed to cover and hold the same.

2. A wrapper made of thin flexible material consisting of two longitudinally extending portions held together and relatively adjustable laterally, each portion having a side flap extending from its side and adapted to overlie the adjacent end of the article inclosed.

3. A wrapper made of thin flexible material consisting of two longitudinally extending portions held together and relatively adjustable laterally, each portion having one edge provided with reinforcing material and a side flap held to the body portion by said reinforcing material.

4. A wrapper comprising two longitudi-

nally extending portions, means for holding said portions together in adjustable relation, each portion having a reinforcing strip of metal connected to one of its edges and a flap portion held by said metal strip, said metal strip being scored to permit it to bend easily in conforming to the shape of a book.

Signed at New York city, in the county of Kings and State of New York this 8th day of July, A. D. 1919.

HERMAN L. GREVE.
